UNITED STATES PATENT OFFICE.

PATRICK WILLIAM GROOM, OF PHILADELPHIA, PENNSYLVANIA, ASSIGNOR TO HIMSELF AND JONATHAN R. SELTZER, OF SAME PLACE.

DESIGN FOR SHOVELS.

Specification forming part of Design No. 5,043, dated June 27, 1871.

To all whom it may concern:

Be it known that I, PATRICK WILLIAM GROOM, of Philadelphia, county of Philadelphia, State of Pennsylvania, have invented or produced a Design for a Shovel-Blade, of which the following is a specification:

Figure 1 in the accompanying drawings is a face view of a shovel-blade made in accordance with my design, and Fig. 2 is a side view of the same.

The blade A is so bent that a transverse section represents part of a circle, oval, parabola, or other equivalent figure, whereby prominent turned-up edges *a a* are produced, these edges gradually vanishing in one direction in a point or rounded end, *b*, and terminating in the opposite direction at the inclined back *d*, the junction of the edges *a a* with the back being either abrupt, so as to present sharp corners, or slightly curved. The back is inclined, and meets the blade A at

the curved line *x*. The front of the blade, instead of being rounded or pointed, as above described, may, in some instances, be cut off square, as shown by the dotted line *y*, without departing from my design, which relates more especially to the form of the rear portion of the blade.

I claim—

The design for a shovel-blade, the rear portion of which is of the form substantially as described, and as illustrated in and by the accompanying drawings.

In testimony whereof I have signed my name to this specification in the presence of two subscribing witnesses.

P. W. GROOM.
